ABSTRACT: A pilot light attachment which may be installed on an electric switch without tools. The attachment is particularly suited for use with a manually operated motor-starter-type switch and includes a pair of springlike members that supply the force for maintaining the switch and attachment assembled and an electric connection between the switch and attachment. The portion of the attachment supporting the bulb is connected to the switch by a three-point suspension which spaces the attachment from the current-carrying parts of the switch to provide the switch current-carrying parts with a maximum convective cooling.

PILOT LIGHT ATTACHEMENT FOR AN ELECTRIC SWITCH

This invention relates to electric switches and more particularly, to a pilot light attachment which may be installed and removed from the switch without the use of tools.

Heretofore, manually operated switches, such as contactors and the like, have been provided with pilot lights for indicating when the contacts of the switch are closed and the power circuit controlled by the switch is energized. In pilot light structures as previously used, conventionally separate mounting means have been employed to attach the pilot light structure to other supporting structures. Further, the wires leading from the pilot light were connected to terminals of the switch so the pilot light would be energized whenever the switch was in an ON circuit-closing position. Thus, the prior art devices required the use of tools to mount the pilot light per se and achieve the electrical connection between the switch and the pilot light. In the device according to the present invention, the use of tools which have been heretofore required to mount the pilot light, have been completely eliminated, so that the device may be conveniently installed or removed from the basic switch and merchandised as a separate item which may be conveniently mounted on the switch when required.

It is an object of the present invention to provide a pilot light attachment for a manually operated switch which may be readily installed on the switch without tools and without disturbing any components of the switch.

Another object is to provide a pilot light attachment for an electric switch wherein the attachment is maintained in position in the switch by a pair of resilient members that also provide an electrical connection between the current-carrying parts of the switch and the pilot light attachment.

An additional object is to provide a manually operated electric switch with a pilot light attachment that may be installed on the switch without tools and will indicate when the switch is in a circuit-closing condition without reducing the convective cooling of the current carrying parts of the switch.

A still further object is to provide a three-point mounting between an electric switch and a pilot light attachment for the switch and to maintain the three-point mounting by a pair of members that also provide an electrical connection between the current-carrying parts of the switch and the pilot light attachment.

Further objects and features of the invention will be readily apparent to those skilled in the art from the specification and appended drawing illustrating certain preferred embodiments in which:

FIG. 1 is a front plan view of an electric switch which may be used with a pilot light attachment that incorporates the features of the present invention.

FIG. 2 is a bottom end view of the switch in FIG. 1.

FIG. 3 is a side view of the switch with a pilot light attachment with a portion of the switch and the pilot light attachment broken away.

FIG. 4 is a perspective view of the pilot light attachment detached from the switch in FIG. 3.

A switch 10, as shown in the drawing, preferably is of the type fully disclosed in an application for U.S. Pat., Ser. No. 9,203, which has been filed by the inventor Jordan F. Puetz concurrently herewith and has been assigned to the assignee of the present application. As disclosed in the Puetz application, the switch 10 includes a switching section 12 and an overload-detecting section 14. The switching section 12 includes a housing 16 that is removably secured to a portion 18 of a base 20. The overload-detecting section 14 includes a portion 22 of the base 20. The base 20 preferably is formed as an integrally molded part which is formed to have a row of spaced compartments in each of the portions 18 and 22 and has a rear wall 24 arranged to be mounted on vertical panel, not shown, by suitable screws which extend through openings 26 in the base. The portion 22 of the base 20 has a front surface 28 which provides entry into the compartments in the

portion 22. Each of the compartments is arranged to include a solder-type current responsive unit which are designated in the respective compartments by the numerals 30, 32 and 34. Each of the current responsive units 30, 32 and 34 has a heater element connected in a circuit to be monitored and a ratchet wheel which is held stationary when the current flow through the heating element does not exceed a predetermined value. The heater elements and the ratchet wheels in the current responsive units 30, 32 and 34 are respectively designated

5 with a suffix *a* and *b* in the drawing. The heater elements 30*a*, 32*a* and 34*a* each have their upper ends, as illustrated in FIG. 1, connected to a conductive strap by a screw 36 and their lower ends connected to individual terminal members 38 by a screw 40 so as to be heated by the current flow passing between the conductor strap that is connected to the screws 36 and the terminal members 38. The heating elements 30*a*, 32*a* and 34*a* when subjected to an excess current will release the respective ratchet wheels 30*b*, 32*b* and 34*b* so as to permit any one of a plurality of sliders, not shown, to move within the portion 22 and cause a release of a trip mechanism within the switching section 12 so that a toggle mechanism within the section 12 will move to a tripped position and cause movable contacts within the switching section 12 to separate from the stationary contacts so as to interrupt the circuit therebetween. The conductive straps 50, to which the current responsive units 30 and 34 are connected respectively, have portions designated by numerals 42 and 44 exposed to the front surface 28. The portions 42 and 44 are each positioned within a 10 socket defined by vertical walls 46 which form a continuation of partitions which define the partitions in the base 20 defining the compartments wherein the current responsive units 32 and 34 are located. The conductive straps 50 also have a portion 47 to which a stationary contact 48 of the switching section 12 is attached.

The housing 16 and a portion of the base 18 form an internal cavity wherein the compartments provided by the base 20 are included. Positioned in each of the compartments is a pair of stationary contacts that are spaced equidistantly on opposite sides of a centerline. The stationary contacts adjacent the upper end of the switch are each electrically connected to a terminal member 52. The stationary contacts adjacent the lower ends of the compartments of the base 18, as illustrated by the stationary contact 48 in FIG. 3, are connected to the portion 47 of the conductive strap 50 so that the current responsive units 30, 32 and 34 may be electrically connected to the stationary contacts of the switch by the screws 36. The housing 16 provides an enclosure for a movable contact carrier which is moved by a toggle mechanism, not shown, from a position wherein movable contacts carried by the carrier are separated from the stationary contacts into a position wherein the movable contacts engage the stationary contacts when the toggle mechanism is actuated. The toggle mechanism is actuated by an OFF operating button 54 and an ON operating button 56, each of which has a portion externally accessible of the switching section 12. The depression of the OFF button 54 will actuate the toggle mechanism so that the movable contacts move to a position where they are separated from the stationary contacts. The operation of the ON button will cause the toggle mechanism to move the movable contacts into engagement with the stationary contacts to complete circuits through the current responsive units 30, 32 and 34.

The housing 16 has a wall 58 extending perpendicular to the top surface 28. Integrally formed as a portion of the housing 16 on the wall 58 are three spaced abutments respectively designated by numerals 60, 62 and 64. The abutments 60, 62 and 64 respectively have bottom surfaces 66, 68 and 70 facing the front surface 28. Extending upwardly in the bottom surfaces 66, 68 and 70 are grooves 72, 74 and 76, which respectively provide surfaces 78, 80 and 82. The surfaces 78, 80 and 82 each confronts and is vertically spaced from the front surface 28. The abutments 60 and 64 are located on the housing 16 so that the surfaces 78 and 82 are spaced from each other and are equidistant from the front surface 28. The abutment

62 is positioned on the wall 58 so that the surface 80 and the surfaces 78 and 82 are unequally spaced from the front surface 28 and the surface 80 is equidistantly spaced between the surfaces 78 and 82.

A pilot lamp attachment 90 for the switch 10 includes a molded body 92, a pair of leaflike spring members 94, a bulb receptacle 96, a pair of leads 98, an incandescent bulb 100 and a support 102 for the bulb receptacle 96. The molded body has a front surface 104, a rear surface 106, a top end 108 and a bottom end 110. Extending between the front surface 104 and the rear surface 106 is a rectangularly shaped opening 112 which is included to aid in the convective cooling of the current responsive unit 32 mounted in the central compartment in the base 20 when the pilot light attachment 90 is secured on the switch 10. Extending from the front surface 104 at the top end 108 of the molded body 92 are three spaced tongues 114, 116 and 118. The tongues 114, 116 and 118 have free ends which are arranged to be respectively received within the grooves 72, 74 and 76 when the pilot light attachment 90 is positioned on the switch 10. The pair of leaflike spring members 94 are secured to the rear surface 106 on opposite sides of the rectangular opening of the body 92. The leaflike members 94 are formed of resilient metal material and have leg portions 122 and 124 which extend rearwardly from the rear surface 106 at the top end 108 of the body 92. The legs 122 and 124 each have a free end curved to provide a foot which are respectively designated as 122a and 124a on the ends of the legs 122 and 124. The bulb receptacle 96 is mounted on the bottom end 110 by the support 102 which extends between the bottom end 108 and a bottom end of the receptacle 96. The receptacle 96 extends parallel to the front surface and has a socket at its top end which receives the bulb 100. Extending from the rear end of the receptacle are the pair of leads 98 each of which has a slip-on type connector 126 on its terminal end. The connectors 126 on the pair of leads 98 are each connected to a portion 120 on the pair of leaflike spring members 94 to provide an electrical connection between the pair of members 94 and the bulb 100. The members 94 extend along the rear surface 106 so the portions 120 are located at the bottom end 110 to permit the connection between the leads 98 and the members 94 to be readily established during the manufacture of the pilot light attachment 90. The legs 122 and 124 are arranged to position the feet 122a and 124a so that the feet are pressed in tight engagement with the portions 42 and 44 of the conductive straps 50 and to form an electrical connection with the portions 42 and 44 on the conductive straps 50 when the pilot lamp attachment 90 is secure in its position on the switch 10. If required the receptacle 96 may also include a portion 128 wherein a resistor which is electrically in circuit with the bulb 100 may be included in a manner well known to those skilled in the art.

The pilot lamp attachment 90 is installed in its position on the switch 10 by manually positioning the attachment 90 so that the feet 122a and 124a are received in the sockets wherein the portions 42 and 44 of the conductive straps 50 are located. When the attachment is thus positioned, it may be secured in its mounted position on the switch 10 by moving the body 92 toward the front surface 28 against the force supplied by the resilient legs 122 and 124 to a position which will permit the tongues 114, 116 and 118 to be respectively received within the grooves 72, 74 and 76 as the top end 108 is positioned adjacent the wall 58. When the manual force on the body 92 is removed, the resiliency provided by the legs 122 and 124 will cause the tongues 114, 116 and 118 to move into the grooves 72, 74 and 76 so that the free ends of the tongues 114, 116 and 118 engage the surfaces 78, 80 and 82 and maintain the attachment 90 in its position on the switch 10. In this connection it should be noted that the groove 74 and the tongue 116 are spaced from the front surface 28 at a greater distance than are the surfaces 78 and 82 and the tongues 114 and 118. Thus the grooves 72, 74 and 76 and the cooperating tongues 114, 116 and 118 will provide a three-point suspen-

sion between the body 92 and the wall 58 to prevent the body 92 from moving from its attached position on the switch 10. It is to be further noted that when the attachment 90 is secured on the switch 10, the rear surface 106 will extend parallel to and be spaced from the front surface 28 to maximize the convective cooling to the current responsive units 30, 32 and 34. Additionally, all that is required to remove the pilot light attachment 90 from the switch 10 is to release the engagement between the tongues 114, 116 and 118 and the grooves 72, 74 and 76 by merely forcing the body 92 rearwardly against the force supplied by the resilient leaflike spring members 94 so that the tongues 114, 116 and 118 may be disengaged from the grooves 72, 74 and 76. The removal of the pilot light attachment may be required to inspect or interchange the current responsive units 30, 32 and 34. When the switch 10 together with its attached pilot lamp attachment 90 is energized, the portions 42 and 44 will have opposite polarity potentials impressed thereon. Thus, the bulb 100 will be illuminated by a circuit that is completed through the members 94 because of the electrical connection that is established between the feet 122a and 124a which are pressed against the portions 42 and 44 so the electrical connection between the pilot light is established automatically when the pilot light attachment 90 is mounted on the switch 10.

While certain preferred embodiments of the invention have been specifically disclosed, it is understood that the invention is not limited thereto, as many variations will be readily apparent to those skilled in the art and the invention is to be given its broadest possible interpretation within the terms of the following claims.

What we claim is:

1. A pilot light attachment for an electric switch, said switch having a pair of spaced conductors exposed on a front surface and a plurality of spaced grooves with each of said grooves providing a surface confronting and spaced vertically from the front surface, said attachment comprising: an insulating body having a front side, a rear side and a plurality of tongues extending from the front side into engagement with the surfaces provided by the plurality of spaced grooves, a pilot light bulb, a receptacle for the bulb positioned by the body so the bulb is exposed from the front side, a pair of leads extending from the receptacle for connecting the bulb in a circuit, and a pair of leaflike spring members each having a first end mounted on the rear surface and connected to one of the leads and a second end engaging one of the spaced conductors for resiliently pressing the tongues into the plurality of spaced grooves and electrically connecting the bulb to the spaced conductors.

2. The structure as recited in claim 1 wherein the switch has two mutually perpendicular surfaces with one of the two surfaces providing the front surface including a pair of sockets wherein the spaced conductors are disposed and the other of the two surfaces providing a support for the plurality of spaced grooves.

3. The structure as recited in claim 2 wherein the plurality of spaced grooves equal three with two of said three grooves providing a pair of surfaces that are spaced from each other and equidistant from the front surface of the switch and the third of the three grooves providing a surface that is equidistant to the surfaces of the said pair of grooves.

4. The structure as recited in claim 3 wherein the body has two ends with one of said two ends providing a support for the receptacle and the other of said two ends extending to provide a portion of each of the tongues.

5. The structure as recited in claim 4 wherein a plurality of current responsive units are mounted on the front surface and the insulating body has an opening therein aligned with one of the current responsive units to aid in the convection cooling of the said one current responsive unit.

6. The structure as recited in claim 4 wherein the receptacle extends along an axis that is parallel to the front side.

7. The structure as recited in claim 4 wherein the resilient members are arranged so the other of said two ends of the

body is pressed into engagement with the said other of said two surfaces of the switch when the second ends of the resilient members are in engagement with the spaced conductors.

8. The structure as recited in claim 4 wherein the receptacle provides a support for a resistor that is electrically in circuit with the bulb.

9. The structure as recited in claim 4 wherein the tongues

each extend in the same direction from the front side of the body and one of the tongues is equidistantly spaced between two other of said tongues.

10. The structure as recited in claim 9 wherein the said one tongue is spaced at a greater distance from the front side than the said other two tongues.
